Primary Examiner — R. Johnson(74) *Attorney, Agent, or Firm* — Jacobsen IP Law; Krista S. Jacobsen(57) **CLAIM**

The ornamental design for a chair, as shown and described.

DESCRIPTION

FIG. 1 is a front view of the chair, showing my new design;
FIG. 2 is a back view of the chair;
FIG. 3 is a top view of the chair;
FIG. 4 is a bottom view of the chair; and,
FIG. 5 is a left side view of the chair, the right side view
being a mirror image thereof.
Portions of the chair shown in broken lines are illustrative
only and form no part of the claimed design.

1 Claim, 5 Drawing Sheets(56)
